UNITED STATES PATENT OFFICE.

WILLIAM L. LEONARD AND NORMAN SUHRIE, OF ALTOONA, AND CLARENCE D. DOUTY,
OF BARREE, PENNSYLVANIA.

BOILER-FEED APPARATUS.

1,282,601.

Specification of Letters Patent. Patented Oct. 22, 1918.

Application filed March 25, 1918. Serial No. 224,450.

To all whom it may concern:

Be it known that we, WILLIAM L. LEONARD and NORMAN SUHRIE, both residents of Altoona, Blair county, Pennsylvania, and CLARENCE D. DOUTY, residing at Barree, Huntingdon county, Pennsylvania, citizens of the United States, have invented certain new and useful Improvements in Boiler-Feed Apparatus, of which the following is 10 a full, clear, and exact description, taken in connection with the accompanying drawings, such as will enable others to make and use the same.

Our invention relates in general to boiler 15 feed apparatus, and has reference more particularly to that type of boiler feed apparatus known as locomotive injectors, our principal aim being to improve the construction and increase the efficiency and utility of 20 apparatus of this type.

Heretofore it has been customary to embody in such apparatus separate and distinct hand operated devices, as wheels, levers and the like, for operating the steam, 25 water supply, and overflow valves, each intended to be separately manipulated by the locomotive engineer, the operation altogether requiring seven distinct movements, so that the engineer's attention at such times 30 would be diverted and arrested from rail and signal conditions.

The principal objects of our invention are; first, to provide means in such apparatus whereby the said valves are all operated and controlled from a single point, *i.e.*, the lever of the steam valve, thereby attaining a simple and compacted structure in which only two movements are required to operate it; second, to provide an apparatus 40 which may be readily assembled and installed and when installed may be easily operated and regulated; third, to provide means in such apparatus whereby a minimum flow of water supply is instantly available and whereby the supply may be conveniently and accurately regulated to provide for a water supply up to the maximum; 45 fourth, to provide means for insuring effective working of the movable valve parts under weather conditions of low temperatures; fifth, to provide in an apparatus of this character a pressure operated means for automatically opening and closing the overflow, and thereby prevent occurrence of 50 water waste due to carelessness or oversight.

of the engineer in forgetting to close his overflow valve while the feed water valve was still open; sixth, to produce an apparatus of this type wherein water pound and valve jamming and locking are eliminated; 60 and seventh, to provide a quick acting apparatus designed to speedily and effectively replenish the boiler and in a manner permitting the engineer to properly control the boiler pressure.

These, together with such other objects as may hereinafter appear or are incident to our invention, we attain by means of a construction illustrated in preferred form in the accompanying drawings, wherein—

Figure 1 is a general view of a locomotive cab and boiler to which my invention is shown applied; Fig. 2 is a central vertical section of the steam valve, illustrating a portion of the connections leading to the 75 water valve and overflow valve; Fig. 3 represents a side elevation of the same; Figs. 4 and 5 are sectional views illustrating the injector proper and the water and overflow valve mechanism; and Fig. 6 is a bottom 80 plan view of the overflow valve.

Referring to Fig. 1 of the drawings, the steam valve 7 has its inlet side connected with a steam supply pipe 8, which in turn, as will be understood, leads to the steam space 85 of the boiler 9. The numeral 10 designates a steam conducting pipe which extends from the discharge side of the steam valve 7 to the inlet side of the injector 11, and with this injector is associated, in a manner hereinafter described, a water valve 12 and an overflow valve 13, the former being connected to the water supply pipe 14 and the latter having an outlet indicated by the numeral 15. The injector 11 in turn is provided with a water conducting pipe 16 which leads to the water space of the boiler.

Referring now more particularly to Figs. 2, 3, 4, 5 and 6, it will be seen that the casing 17 of the steam valve 7 is formed with a septum or diaphragm 18 intermediate the inlet side 19 and the outlet side 20 of the casing, and this diaphragm is provided with an opening 18^a normally closed by the piston valve 21, which has a downward extension 105 22 formed with a passage 23 disposed in alinement with a passage 24 that extends through a neck 25 formed on the side of the casing. A port 26 is formed in the wall of the piston valve 21 in order to provide com- 110

munication between the inlet side 19 of the casing and the passage 23, the latter being controlled by a pilot valve 27 whose stem 28 is carried in the stuffing box 29 of the valve, 5 the lifting of which by the lever 30 will first permit a flow of steam from the inlet side 19 through the port 26 and thence downwardly through the passages 23 and 24 to the pressure conducting pipe 31, whose lower 10 terminal 31^a is connected by the union nut 32 to the inlet 33 of the piston chamber 34, which latter is associated with the upper portion 35^a of the overflow valve body 36.

Further movement of the lever 30 brings 15 the upper face of the valve 27 against a plug 37 which is screw-threaded into the upper portion of the piston 21, which causes the piston valve 21 to lift from its seat clear of the valve opening 18^a in the diaphragm 18 20 in order to permit full communication between the inlet and outlet sides of the steam valve. In order to obtain the desired lever- 25 age, the lever 30 is pivoted at 38 on the valve stem 28 and is provided at its outer end with a fulcrum link 39 pivotally mounted at 40 upon a yoke 41, which latter is centered on the valve body just below the stuffing box 29 and is supported by a horizontally extending flange 42. Opposite move- 30 ment of the lever and valve 27 first closes the passage 23, whereupon the piston valve seats downwardly and closes the valve opening 18^a.

The casing 36 of the overflow valve 13 35 (Fig. 5), is provided centrally with a septum or diaphragm 43 which is connected with the injector at 44 to receive the overflow therefrom, the inner end of said dia- 40 phragm constituting a seat 45 for the valve 46, which normally closes off the overflow passage 47 from the outlet chamber 35. This valve is held against its seat by the stem 48 of a piston 49 through the medium 45 of the coil spring 50 whose upper end takes against the head of the piston chamber 34.

This stem is hollowed or recessed at 51 to 50 slidably receive the stem 46^a of the valve 46, and when the piston 49 lifts, the wall of said recess serves to guide the stem of the valve 46 when the pressure exerted by the over- 55 flow is sufficient to raise it from its seat 45. Below the head 49^a of the piston and the inlet 33 is a seated plate or diaphragm 51^a, and intermediate said head and plate is a 60 chamber 52 into which pressure from the inlet 33 flows when the pilot valve 27 rises to reduce the pressure above the piston valve 21. The introduction of pressure into chamber 52 raises the piston 49 clear of the overflow valve, there being an exhaust port 53 formed in the casing wall above the head 49^a to permit the piston to rise. Upon the closing of the pressure conducting passages 23 and 24 by the pilot valve 27, the piston 65 49 again returns to its normal position where

it holds the valve 46 against its seat, this movement being permissible through the reduction of pressure and the action of the compression spring 50. A supplementary exhaust passage 54 may be additionally provided if desired. 70

It will therefore be clearly understood from the foregoing description that the overflow valve disk 46 automatically opens and closes upon the opening and closing of 75 the passage 23 by the pilot valve 27. The latter, upon being lifted in the initial movement of the lever 30, equalizes the pressure above and below the piston valve 21, thus facilitating the lifting of the latter by the 80 lever, whereupon the injector 11 receives a flow of steam from the steam conducting pipe 10 in order to exert the required injecting force or pressure upon the water which the injector receives from the water 85 valve casing 12 via the pipe 14 and passages 55 and 56.

The passage 56, which is disposed laterally with respect to the inlet passage 55, provides communication between the said passage and the injector at a point intermediate the upper steam and jet nozzles 57 and the lower nozzles, namely, the intermediate nozzle 58, combining nozzle 59, 59^a, and delivery nozzle 60, the latter directly communicating 95 or delivering the feed water to the delivery pipe 16, and from thence to boiler 9. This injector nozzle construction is old and well known, consequently further description is 100 not deemed necessary.

The reference numeral 61 designates the bonnet of the water valve casing 12, and 62 the valve disk which rests upon the seat 63 disposed intermediately of and controlling the flow of water through the passages 55 105 and 56. Extending through the bonnet 61 is a spindle or connecting rod 64 connecting the water inlet valve 62 and an eccentric strap 65 disposed about the yoke 41 eccentrically of the axis of the steam pilot valve 110 stem 28. Relative movement of the yoke 41 is obtained by manipulating the lever handle 30 in a direction or directions at right angles to the direction of movement of the lever when unseating the valves 21 and 27, 115 and through the medium of the strap 65 the rod 64 is raised or lowered to unseat or seat valve 62 that controls the water inlet. Preferably this valve has its under face cross-grooved, the grooves 62^a being carried high 120 enough beyond the seat 63 to normally permit the flow of a minimum supply of water past said seat to the passages 56 and 47, and which minimum supply is available instantly to cool the injector and for action thereupon 125 by the steam jet in the injector.

In order that the water supply be controlled and regulated from the predetermined and minimum flow to the maximum quantity desired, we form the flange 42 with 130

a socketed extension 42', in the socket 66 of which is a spring-actuated finger or dog 67 having a beveled outer portion adapted to yieldingly engage with the beveled teeth or 5 graduations 68 of an indicator member 69 formed integral with the yoke 41. These teeth may indicate the water flow from zero (z) or minimum, to whatever maximum (x) may be desired, and the indicator is so 10 constructed and positioned that any increase or decrease desired in the water flow may be conveniently regulated and controlled by the engineer without appreciable detraction from his survey of rail and signal conditions.

15 To operate the apparatus, the engineer applies a pull on the lever 30 in a direction toward himself, which movement, as in the manner already described, effects (1) the unlocking of the overflow valve so that it may 20 lift automatically under pressure, and (2) the introduction of the full pressure of the steam upon the already available minimum water supply flowing past valve 62 into chamber 56 to force the same through the 25 injector to its delivery side. Then at his leisure the engineer may tilt or move side- 30 wise the lever 30, and with it the yoke 41, until the latter registers the desired water flow at the indicator 67, which may be any- 35 where between z and x. This movement, as already indicated, raises the rod 64 and with it the water control inlet valve 62. Opposite movement of the lever reverts the parts 40 to their normal condition.

45 We do not intend to restrict ourselves to the precise details of construction shown, or to the exact arrangement of the various parts, as it is obvious that modifications and variations thereof may be made without in 50 any way departing from the spirit and scope of our invention as pointed out in the following claims.

What we claim is:

1. In boiler feed apparatus, the combination of an injector having a water conducting valve, a steam supply device having direct connections with said injector and said valve and provided with means for controlling and operating said connections includ- 5 ing a manually actuatable member, said member mounted in said device for dissimilar directional movement during the controlling of said connections by said means, and a water indicating device associated with said member and capable of indicating water flow during movement of said member in one direction.

2. In boiler feed apparatus, the combination of an injector having a water conducting valve, a steam supply device having direct connections with said injector and said valve and provided with means for controlling and operating said connections includ- 5 ing a manually actuatable member, said member mounted in said device for dis-

similar directional movement during the controlling of said connections by said means, and an indicator device for the water supply valve operative during actuation of the said member in one of its directional 70 movements.

3. In locomotive boiler feed apparatus, the combination with associated steam and water supply lines, of valves therefor, an indicator device having a connection with 75 the valve for the water supply line, and a common means for actuating said connection and the valve for the steam supply line.

4. In locomotive boiler feed apparatus, 80 the combination of a feed water line, a valve in said line, a steam injecting mechanism for said line having an overflow device and provided with a hand operated actuating member, and a water controlling connection 85 to said valve provided with a flow regulating and indicating device mounted about said member, said devices and said connection constructed and arranged for actuation by said actuating member.

5. In boiler feed apparatus, the combination of an injector having an overflow valve and a water supply valve, a steam supply valve casing provided with connections with said valve and said injector, part of said 95 connections constituting separate pressure conducting passages leading independently from the interior of said steam supply valve casing to the injector and one of said valves, and a common actuatable means operatively 100 associated within said steam supply valve casing and constructed for permitting a flow of pressure first through the passage to the valve and then through the passage to the injector.

6. In locomotive boiler feed apparatus, the combination of an injector having a steam inlet and a water receiving inlet, a steam supply line having a starting lever, a water supply line supplying water to said inlet, a 110 normally closed overflow passage leading from said injector, a steam supply valvular mechanism operatively positioned with reference to said starting lever and provided with separate pressure conducting conduits lead- 115 ing to said steam inlet and said overflow passage, said mechanism comprising parts thereof controlling said conduits and constructed and arranged upon actuation of the starting lever to automatically open the 120 overflow passage in advance of the flow of pressure to the steam inlet.

7. In locomotive boiler feed apparatus, the combination of an injector having a steam inlet and a water receiving inlet, a 125 steam supply line having a starting lever, a water supply line supplying water to said inlet, a normally closed overflow passage leading from said injector, a steam supply valvular mechanism operatively positioned 130

- with reference to said starting lever and provided with separate pressure conducting conduits leading to said steam inlet and said overflow passage, said mechanism comprising parts thereof controlling said conduits and constructed and arranged for operation to automatically open the overflow passage in advance of the flow of pressure to the steam inlet, one of said parts actuated by the 10 starting lever and the other pressure actuated.
8. In boiler feed apparatus, the combination of an injector having an overflow casting provided with a valve and a relatively 15 movable piston therefor, said piston normally holding said valve closed, a steam supply valve having a pressure conducting passage leading to the casing to raise said piston, a manually operated controlling device for said steam supply valve, said overflow valve capable of independent opening and closing movement when the piston is in raised position, and a steam conducting passage intermediate the steam supply 20 valve and the injector.
9. In boiler feed apparatus, the combination of an injector having an overflow casting provided with a valve and a relatively movable piston therefor, said piston normally holding said valve closed, a steam supply valve having a pressure conducting passage leading to the casing to raise said piston, a manually operated controlling device for said steam supply valve, said overflow 25 valve capable of independent opening and closing movement when the piston is in raised position, and a steam conducting passage intermediate the steam supply valve and the injector adapted to be controlled by said device, said device constructed to permit a flow of steam first through the first-mentioned passage and then through the last-mentioned passage.
10. In locomotive boiler feed apparatus, the combination with an injector and steam and water supply lines leading to said injector, of valvular means for said lines, an actuating member therefor an indicator device for the water supply line comprising a 45 fixed member associated with said steam line and a co-operating movable member operatively connected with the valvular means for the water supply line and actuatable by said actuating member.
11. In boiler feed apparatus, the combination of an injector having a steam inlet and an overflow passage, an overflow valve, means adapted for normally holding said valve seated in said passage, a steam supply 50 valvular mechanism having a pressure actuated member and steam conducting connection with said inlet, and a fluid conducting means for said overflow valve, said member and said means constructed and arranged 55 with reference to said connection for opera- tion to lift said valve seating means and thereby open said overflow passage in advance of the flow of steam through said connection to said steam inlet.
12. In boiler feed apparatus, the combination of an injector having a steam inlet and an overflow passage having a valve normally held closed, a steam supply valve having an actuating member and a steam conducting pipe adapted to conduct steam to said inlet 70 when said member is actuated, means operative for automatically releasing said overflow valve upon actuation of said member including a pressure controlled member in said steam supply valve, and a water supply pipe 80 in communication with the discharge side of said injector, said means constructed and arranged to permit the overflow passage to open in advance of the flow of steam from said steam supply valve through said inlet. 85
13. In locomotive boiler feed apparatus, the combination with an injector and steam and water supply lines leading to said injector, of valvular means for said lines, an actuating member therefor, an indicator device for the water supply line comprising a fixed member associated with said steam line and a co-operating movable member operatively connected with the valvular means for the water supply line and actuatable by 90 said actuating member, said last mentioned valvular means including a valve constructed when seated to permit a flow of water toward and into the injector and capable of being unseated by said movable member to 95 increase such flow of water, the indicator device being constructed and arranged to register such increase of flow.
14. In locomotive boiler feed apparatus, the combination of an injector having a steam inlet and a water receiving inlet, a steam supply line having a starting lever, a water supply line supplying water to said inlet, a normally closed overflow passage leading from said injector, a steam supply 105 valvular mechanism operatively positioned with reference to said starting lever and provided with separate pressure conducting conduits leading to said steam inlet and said overflow passage, said mechanism comprising parts thereof controlling said conduits and constructed and arranged for operation to automatically open the overflow passage in advance of the flow of pressure to the steam inlet, said water supply line constructed to deliver water to the overflow passage co-incident with the advance opening thereof. 110
15. In locomotive boiler feed apparatus, the combination with an injector having a steam inlet and steam and water supply lines leading to said injector, of a normally closed overflow passage in said injector, a compound valvular mechanism for said steam line provided with a pressure conducting 115
- 120
- 125
- 130

- conduit controlled by a valve part of said mechanism and leading to said inlet, and having a pressure conducting conduit independently controlled by another valve part 5 of said mechanism constructed and arranged to open the overflow passage in advance of the flow of steam to the injector inlet, said water supply line organized to deliver a supply of water to the injector co-incident 10 with the advance opening of the said overflow passage.
16. In locomotive boiler feed apparatus, the combination with an injector having a steam inlet and steam and water supply 15 lines leading to said injector, of a normally closed overflow passage in said injector, a compound valvular mechanism for said steam line provided with a pressure conducting conduit controlled by a valve part of 20 said mechanism and leading to said inlet, and having a pressure conducting conduit independently controlled by another valve part of said mechanism constructed and arranged to open the overflow passage in advance 25 of the flow of steam to the injector inlet, and one of said parts of said valvular mechanism associated in said steam line with the other part for relative automatic operative movement.
- 30 17. In locomotive boiler feed apparatus, the combination with an injector having a steam inlet and steam and water supply lines leading to said injector, of a normally closed overflow passage in said injector, a compound valvular mechanism for said steam line provided with a pressure conducting conduit controlled by a valve part of said mechanism and leading to said inlet, and having a pressure conducting conduit independently controlled by another valve part 35 of said mechanism constructed and arranged to open the overflow passage in advance of the flow of steam to the injector inlet, said water supply line organized to deliver a 40 supply of water to the injector co-incident with the advance opening of the said overflow passage, one of said parts of said valvu- 45 lar mechanism associated in said steam line with the other part for relative automatic operative movement, the other said part provided with a starting lever operative to permit relative movement of the aforesaid part. 50
18. In boiler feed apparatus, the combination of an injector having a steam inlet and a water inlet, a steam supply line having a starting lever, an overflow passage leading from said injector, a check valve normally closing said passage, a water supply line normally in communication with said passage through said water inlet, and a valvular mechanism for said line provided with separate pressure conducting conduits leading to said steam inlet and said overflow passage, said mechanism constructed and adapted upon actuation of said starting lever for operative movement with reference to said conduits to automatically permit the opening of the overflow passage valve in advance of the flow of pressure through the conduit leading to the steam inlet. 55 60 65 70
19. In boiler feed apparatus, the combination of an injector having a steam inlet and a water inlet, a steam supply line having a starting lever, a normally closed overflow passage leading from said injector, a water supply line normally in communication with said passage through said water inlet, and a valvular mechanism for said line provided with separate pressure conducting conduits leading to said steam inlet and said overflow passage, said mechanism constructed and adapted upon actuation of said starting lever for operative movement to permit the opening of the overflow passage in advance of the flow of pressure to the steam inlet, means associated adjacent the water inlet for increasing the flow of water to the injector, and water flow indicating mechanism operatively organized with said means and said starting lever. 75 80 85
